WILLIAM H. LOTZ AND FREDERICK BAUMANN, OF CHICAGO, ILLINOIS,
ASSIGNORS TO WILLIAM H. LOTZ

Letters Patent No. 66,979, dated July 23, 1867.

IMPROVED BRICK MACHINE.

The Schedule referred to in these Letters Patent and making part of the same.

TO ALL WHOM IT MAY CONCERN:

Be it known that we, W. H. Lotz and F. BAUMANN, of Chicago, in the county of Cook, and State of Illinois, have invented certain new and useful improvements in Brick Machines; and we do hereby declare that the following is a full, clear, and exact description thereof, reference being had to the accompanying drawings, making a part of this specification, and to the letters of reference marked thereon, like letters indicating like parts wherever they occur.

To enable others skilled in the art to construct and use our invention, we will proceed to describe it.

Our invention consists in a novel construction of a machine for the manufacture of bricks, the invention consisting more especially of new devices or features in those parts of the machine which press the clay to form the bricks, as hereinafter explained.

Figure 1 is a rear elevation.

Figure 2, a longitudinal vertical section of the same, taken on the line $x-x$ of fig. 1.

Figure 3 is a vertical section of the mould and follower, together with the toggle-joint, for operating the same, somewhat modified.

Figure 4 is a vertical section of the grinding and screening apparatus, taken on the line $y-y$ of fig. 5; and Figure 5 is a vertical section, taken on the line $z-z$ of fig. 4.

We construct a strong upright frame, A, of any suitable size and form, and in the upper part of it secure a heavy metal plate, B, in the centre of which are made one or more rectangular openings, C, of proper size and form to operate as moulds in which to press the brick. Directly under these moulds C is placed a strong metal block, H, from the upper end of which projects a series of plungers, I, of suitable size to correspond with the moulds C. This block H is arranged to slide vertically, and is operated by a toggle-joint lever, which will be hereinafter explained. Above the mould, and to the rear of it, is located a hopper, D, into which the prepared clay is delivered by an endless apron, as represented in fig. 2. A slide, E, is arranged to slide transversely under the hopper D and over the top of the plate B, in which the moulds are formed, there being an opening, E', in the slide, which becomes filled with the clay when under the hopper, and from which it drops through into the mould C when the slide comes over the latter. At its front end this slide is provided with a solid portion, F, of proper size to form a cover to the mould C, as shown in fig. 2. Directly over the moulds, and just above the slide E, is placed an eccentric or cam, J, which rests against and is bedded in a solid metal block, J', secured firmly in place. This cam J is so arranged that when the block F of the slide is over the mould, the cam will be rotated sufficiently to wedge the block F firmly in position while the brick is being pressed, the cam being rotated in an opposite direction, to release the block F as soon as the pressing is done, those movements of the cam being effected by means hereinafter explained.

Within the moulds a series of pins, e, of any required number, is secured in a vertical position, their upper ends coming flush with the top of the mould, their bodies extending down through holes in the plunger I, and being secured rigidly at their lower ends to a cross-bar, a, as shown in fig. 2, the interior of the block H being hollowed out, to permit it to slide up and down, to operate the plunger I without interfering with the pins e. The object of these pins is to form perforations in the bricks; but it is obvious that, if desired, the pins may be omitted, and then the brick will be made solid, the plunger I of course being left solid in that case.

The plunger I, which first presses the brick in the mould, and then pushes the brick up out of the mould, is operated by a double toggle-lever of peculiar construction. This lever consists of two arms, each having two legs, as shown in fig. 2. The legs G and G', as they are brought into a vertical line, raise the plunger, and thereby press the brick, the block F then being in position over the mould and holding the clay in. As soon as this is done the block F is removed or drawn back, when the toggle-lever is pushed still further over, bringing the legs Y and Y' into contact, and they being longer than the legs G G', of course raise the plunger I still higher in the mould, thereby pushing the brick up out of the mould, the slide E coming forward just at that time, and shoving the brick forward on the table C'.

For operating the toggle-lever, the slide, and the cam J, we locate in the lower portion of the frame a shaft, K, on which is secured a wheel, R, which is operated by a driving-pinion, S, secured to a shaft, L. On

the same shaft K are also secured two large cams, V and T, as shown in fig. 2. To the lower arm of the toggle-lever a lever, N, is secured, which projects backward over shaft K, where it is provided with a friction-roller, P, against which the cams V and T press to operate the toggle-lever, the cam V first raising the arm N far enough to bring the legs G and G' in a vertical plane, by which the brick is pressed, the cam T then following and raising the arm N still further, and bringing the legs Y and Y' into a vertical line, and thereby pushing the brick out of the mould.

To the rear end of the lever N is secured a vertical arm, U, which extends down behind the shaft K, and has its lower end resting on an eccentric, g, which is secured to a shaft, t, on which is a wheel, m, operated by a screw or worm, l, on a vertical rod, i, as shown in figs. 1 and 2. On the inside or front face of this arm U is a small lug, n, and on the hub of the cam V is a similar projection, u. When the brick has been pressed, the legs G and G' of the toggle-lever will stand vertically; and, owing to the great pressure on them, they will so remain unless moved; and just at this point the projection u will come into contact with the lug n, and hooking on to it, will carry the arm U downward, thereby pulling the toggle-lever backward slightly, when its own weight will carry it the balance of the distance.

As it is obvious that the capacity of the mould to receive the clay will regulate the quantity which it will receive from the slide, and as this capacity is dependent on the distance to which the plunger I is withdrawn from the mould, it follows that by turning the eccentric g so as to let the arm U fall a greater or less distance, the distance that the plunger I will move or be withdrawn from the mould, and consequently the capacity of the mould and the amount of clay deposited therein, may be regulated at will by simply turning the rod i.

The motions to the slide E and the cam J are imparted by means of levers operated by cam-grooves on the faces of the wheel R. A rock-shaft, O, is secured across the frame, just above the wheel R, and to this shaft are secured two arms h, which are pivoted at their upper ends to links connected to the slide E. Another arm, f, extends from said shaft O, and has a pin or wrist at its lower end, working in a cam-groove of such form or configuration as to impart to the slide the threefold motions, as follows: first, an entire forward movement, for removing the brick raised out of the mould and charging the mould with fresh clay; then back far enough to bring the solid portion E over the mould, where it remains until the brick is pressed; then entirely back, under the hopper D, the form of this groove B* being shown in dotted lines in fig. 2.

To the cam J is secured a lever, c, which has a weight, b, on it. To this lever c is pivoted a vertical rod, d; to the lower end of which a friction-roll is secured on a wrist that travels in a cam-groove, A*, which is so arranged as to raise the lever c and release the cam J at the instant that the pressing is finished and it is desired to remove the cover F, the groove permitting the lever c to drop at the instant that it is desired to close the mould for pressing the brick. By these means all the required movements of the various parts are effected automatically at the proper times, and thus the process is rendered continuous.

In fig. 3 is shown a modification of the plunger and toggle-lever, the latter, in this case, having three legs to each arm, and the faces v extending from r to e, and from x to o', forming a cam by which the brick is pressed.

Instead of the pins e a block, w, is secured in the centre of the plunger H, having its upper end rounded or bevelled. This block w rests at its lower end on a spring, k, so that if there is an excess of material in the mould when the pressing takes place, the block w will yield, and permit the excess to form a thicker wall above it, and thus prevent undue strain on the machine or mould. In this manner brick may be made hollow, or with cavities in them, thus being rendered lighter, using less material, being easier burned, and forming a wall filled with air-spaces, and therefore dryer. This is more especially adapted to the forming of concrete brick, as it is well known that such material will not bear compression equal to clay, and is therefore much more likely to injure the machine.

To prepare the clay for the press, we first grind it between two or more smooth iron rollers, as represented by W in fig. 4. The clay being thus pulverized, then falls upon a shaking-riddle or screen, Z, which consists of a series of iron bars placed parallel with each other, as represented in cross-section in fig. 5, and mounted in a frame having one end pivoted to the frame of the grinding apparatus, as at o' of fig. 4, the opposite end being connected by a rod, b', at each corner, to a bar, d', the opposite end of this latter bar being pivoted to a standard on the frame, as at f' of fig. 4, and resting on a cam-wheel attached to the outer end of one of the rolls W, as represented at u' of fig. 4. It will be seen that as the rolls revolve the cam will impart to the screen Z a vertical motion, similar to that of a flour-bolt, by which the fine particles of clay will be shaken through the screen and fall into the hopper underneath, where they will be taken by the elevator and delivered to the hopper D, ready to be fed into the moulds by the slide E. Any particles which are too coarse to pass readily through the screen will roll off at the lower end, the latter being more or less inclined for that purpose.

In using our machine it is intended to use the clay as it is dug from the bank, the same being dried if too wet to grind readily. If it be found too dry after it is ground and sifted, we propose to temper it by the use of steam, which we propose to inject among the clay in a finely divided state, so as to saturate the mass to any required extent before delivering it to the moulds for pressing.

By these means we construct a machine that is strong, simple, and durable, and that can be used for making clay or concrete brick, as may be desired.

Having thus described our invention, what we claim, is—

1. A double toggle-lever, having two or more sets of legs, arranged to come into operation successively, for the purpose of first pressing the brick in the mould, and then removing the same therefrom, substantially as described.
2. The slide E, for delivering the clay to the moulds, and having attached to and moving with it a solid

portion or metal block, F, to operate as a cover to the mould during the operation of pressing the brick, substantially as set forth.

3. We claim the cam J, when arranged to hold the cover of the mould while the brick is being pressed, substantially as described.

4. We claim the stationary pins e, located in the mould, and having the plunger that presses the brick slide on or around the pins, as and for the purpose set forth.

5. We also claim the use of the supplementary plunger w, resting on or supported by a spring, and having the plunger I arranged to slide on or around it, for the purpose of accommodating itself to the quantity of material in the mould, substantially as described.

6. We claim regulating the amount of material delivered to the mould by adjusting or limiting the distance that the pressing-block or plunger is withdrawn from the mould, substantially as described.

7. We claim the screen Z, arranged to operate in combination with the crushing-rolls W, and having a vertical motion imparted to it, substantially in the manner shown and described.
